UNITED STATES PATENT OFFICE.

LLOYD W. PENNELL, OF BRAINTREE, MASSACHUSETTS, ASSIGNOR TO THE TARBOX TIME REGISTER COMPANY, OF PORTLAND, MAINE.

CIRCUIT-CONTROLLING DEVICE FOR WATCHMEN'S TIME-RECORDERS.

SPECIFICATION forming part of Letters Patent No. 333,293, dated March 23, 1886.

Application filed July 24, 1885. Serial No. 172,507. (No model.)

To all whom it may concern:

Be it known that I, LLOYD W. PENNELL, of Braintree, county of Norfolk, State of Massachusetts, have invented an Improvement in 5 Circuit-Controlling Devices for Watchmen's Time- Detectors, of which the following description, in connection with the accompanying drawings, is a specification, like letters on the drawings representing like parts.

10 My invention relates to a watchman's time- detector of that class in which a record is made by the watchman operating a circuit-closer at the different stations under his care, and has for its object to provide the said detector with 15 a circuit-controlling device, which is simple in construction and most efficient in operation, thereby insuring a surer and more reliable contact between the members of the said circuit- controlling device than has been obtained 20 heretofore in instruments of this class.

In accordance with my invention I have mounted a disk of insulating material upon a metallic shaft having bearings in suitable standards, the shaft being electrically connected through the standards with the usual 25 magnet, which operates the marker or recording device in a manner substantially as described in United States applications Serial No. 162,128, dated April 13, 1885, and No. 30 162,102, dated April 13, 1885.

Instead of the cylindrical drum and shaft of the circuit-controlling device shown in the said applications, I have provided a disk with metallic studs, which are distributed at equal distances apart over its surface and preferably near its circumference, the number of the said 35 studs corresponding to the number of stations to be controlled by the detector. The studs referred to extend through the said disk, and 40 the shank of each stud is connected by a wire with one terminal of a normally-open circuit-closer situated at each of the different stations to be visited by the watchman. The said studs are preferably provided with flat heads, which 45 are brushed over in rotation by a metallic brush or arm, thereby obtaining a rubbing contact between the said brush and stud, and the said brush or arm is connected to a metallic shaft in any suitable or convenient manner, 50 and revolves with it when the said shaft is re-

volved by pallets engaging a toothed wheel on the said shaft in a manner substantially as described in the applications referred to.

Figure 1 is a diagram of a watchman's time-detector embodying my invention, it illustrating the connection between the different stations and my improved circuit-controlling device. Fig. 2 is a side elevation of the detector, showing my improved circuit-controlling device; and Fig. 3 is a detail to be referred to. 60

The plate A, gear c², beam c³, rotating shaft c, and marker b, rotating thereon, pinion c', meshing with the gear c², arbor d, rotated by the clock-work d', sleeve d⁵, upright d⁴, yoke d², magnet f, armature-lever e, spring g, pallets m, and toothed wheel n are all substantially the same as described in United States applications, Serial No. 162,128, dated April 13, 1885, and No. 162,102, dated April 13, 1885, the operation of the parts enumerated being 70 the same as described in the said applications and not herein claimed.

To enable the time-detector to be operated by currents of varying strength, which variation might arise from numerous causes—such as the weakening of the battery or extra resistance being thrown into the circuits—I have provided the said detector with a small shaft, k, having bearings in uprights or standards 6 6, provided with arms 9 9, by which they are 80 secured to the plate A of the detector, and to the said shaft is secured the toothed wheel n, which co-operates with the pallets m. A brush or arm, 5, preferably brass, is mounted upon and revolves with the shaft k. Concentric with 85 the said shaft, and secured to one of the standards 6 in any suitable manner, is a disk, D, of insulating material, the said disk being provided with metallic studs or pins t, which are distributed over its surface and preferably 90 near its circumference, the same being in the path of revolution of the brush or arm 5. The studs are preferably provided with flattened heads, with which the brush or arm 5 makes a rubbing contact as it sweeps over them, 95 thereby insuring good electrical connection between the said arm and studs and preventing any increase of resistance in the circuits which might arise from the accumulation of dust on the said studs.

The number of stations to be controlled by one time detector corresponds to the number of studs on the disk D, the said number being herein shown as twelve.

- 5 I have shown in Fig. 1 the studs 1^x to 12^x, inclusive, the said studs being clearly shown in Fig. 2 as connected by wires n² with the binding-post 1' 2² 3³, &c., each of the said posts being connected by one of the wires n³ n⁴ to one terminal of a normally-open circuit-closer, r, at each station, the other terminal of the said circuit-closer being connected by the wire n⁴ with one pole of the battery B, the other pole being connected to the binding-post 15 o by the terminal wire 15 of the magnet f, the other terminal wire, 16, being connected in any suitable manner with one of the metal arms 9.
- To explain the operation of my improved time-detector, I have shown the circuit of station 2 as closed, the arm or brush 5 being in contact with the flattened head of the stud marked 2^x, as clearly shown in Fig. 2, it being supposed that the watchman is making his record from the said station. With the operating parts in the position shown, the current will pass from the positive pole of the battery B, by wire n⁴, to station 2; from station 2, by wire n³, to the binding-post 2²; from the said binding-post, by wire n², to the stud 2^x; from 20 the said stud, by the arm 5, shaft k, arm 9 of the upright 6, and wire 16, through the magnet f; from the said magnet, by wire 15, to the binding-post o, and thence back, by wire 15, to the negative pole of the battery B. As the 25 current passes through the magnet f it magnetizes the same, which attracts its armature

and operates the marker in the manner described in the applications above mentioned. By the magnet f attracting its armature the shaft k and arm or brush 5 are rotated the 40 space of one tooth of the wheel n, thereby placing the said arm in connection with that one of the studs t marked 3^x, so that the next station from whence a record can be made is station 3.

45 By employing a revolving contact brush or arm, 5, and a stationary insulating-disk provided with contact-pieces I obtain a circuit-controlling device easy in operation and reliable in the performance of its work.

50 In the drawings I have designated the stations 1 to 12, inclusive, and I have designated the studs t, which are in circuit with the said stations, as 1^x to 12^x, inclusive.

55 I claim—

In a watchman's time detector, a clock or motor and a recording device operated by the watchman at different or distant stations, combined with a circuit-controlling device consisting of a metallic arm or brush rotated by a 60 shaft and a disk of insulating material provided with studs or pins co operating with the said arm or brush, to operate substantially as described.

In testimony whereof I have signed my name 65 to this specification in the presence of two subscribing witnesses.

LLOYD W. PENNELL.
